UNITED STATES PATENT OFFICE.

PERCY B. CAMP, OF MAYWOOD, ILLINOIS, ASSIGNOR TO UNIVERSAL DRAFT GEAR ATTACHMENT COMPANY, A CORPORATION OF ILLINOIS.

BRAKE MECHANISM FOR RAILWAY CARS.

Application filed January 7, 1924. Serial No. 684,792.

To all whom it may concern:

Be it known that I, Percy B. Camp, a citizen of the United States, and resident of Maywood, county of Cook, and State of Illinois, have invented certain new and useful Improvements in Brake Mechanism for Railway Cars, of which the following is a specification and which are illustrated in the accompanying drawings, forming a part 10 thereof.

This invention relates to brake mechanisms for railway cars and has for its principal object to permit the anchored end of the brake chain or cable to be easily adjusted with accuracy by unskilled labor.

A further object of the invention is to produce an article of manufacture that can be supplied to car owners at low cost and readily substituted by them for the conventional chain anchorage.

Further objects and advantages of the invention will become apparent as the disclosure proceeds and the description is read in connection with the accompanying drawings illustrating the preferred embodiment of the invention, and in which—

Fig. 1 is a side elevation showing a portion of the hand brake mechanism and the dead end of the chain anchored to the brake 30 step by the improved anchorage device;

Fig. 2 is a perspective view of the device as an article of manufacture;

Fig. 3 is a transverse section on the line 3—3 of Fig. 2, and

Figs. 4 and 5 are perspective views of the yoke and the key respectively, forming parts of this embodiment of the invention.

Referring to Fig. 1, a portion of the car underframe appears at 10 equipped with a 40 brake step 11 in which is suitably journaled a brake staff 12. The power of this staff is communicated to the brake rod 13 through a chain 14, running over a sheave 15 and having its dead end anchored to the step according to this invention.

The preferred embodiment of the invention includes a yoke 16 adapted to straddle the bottom of the step 11, a bow 17 having its arms adjustably mounted in the yoke and 50 a key 18 adapted to pass through the yoke and the brake step, and at the same time secure the bow in the yoke.

As will be seen in Figs. 1, 2 and 4, the yoke is substantially U-shaped, having arms 55 19 adapted to receive between them the

lower portion of the brake step 11 or any other suitable portion of the car. The base 20 of the yoke is perforated at diagonally opposite corners, as indicated at 21 and 22, to form passages for the arms 23 and 24 of the bow, and these passages extend in enlarged form along the adjacent sides of the arms 19. In the present illustration these arms are rectangular in cross section and the passages correspond in form. The arms 19 of the yoke are equipped with aligned perforations 25 adapted to receive the key 18 which also passes through a perforation in the step 11. This arrangement places the key between the arms 23 and 24 and in order to provide a locking engagement, the key and the arms are equipped with complementary teeth 26 and 27, and 28 and 29; and the walls of the perforations 25 are provided with similar teeth 30 and 31. The arms 23 and 24 are elongated and are toothed for a considerable distance. This permits the bow to be secured in a number of different positions with respect to the yoke and, therefore, provides for a number of adjustments in the length of the chain.

When a brake mechanism has been in service for a period the slack increases and causes a corresponding increase in the length of time necessary to apply the brakes. In brake mechanism using quick take-up devices, as, for example, that illustrated at 15, it is important that the length of the chain bear a definite relationship to the other parts. The present invention permits the adjustment to be easily and quickly accomplished by merely withdrawing the key 18, slipping the bow 17 a little further into the yoke and returning the key 18 to position. As the only fastening required is a cotter pin 32, this becomes a very simple operation.

By having the arms 23 and 24 pull against the key above and below the brake step, the load on the key is distributed and the tendency to work out is practically eliminated. By having these arms engage opposite sides of the key, rotation thereof is eliminated.

For simplicity I have shown and described the chain anchored to the brake step not with the intention of being limited thereby, and the language of the claims is to be construed to cover the application of this invention to any fixed or relatively fixed part of the car. In fact, the claims are not to be

limited by the descriptive terms or the illustration, but only by the prior art.

I claim as my invention:

1. In a brake mechanism for railway cars, the combination of a brake chain, a yoke, a key secured to the yoke and a bow secured to the chain and engaged with the key on opposite sides thereof.
2. An article of manufacture including a yoke having passages therein, a bow having arms in said passages, and a key engaging the yoke and cooperating with opposed faces on the arms of the bow to secure the bow to the yoke.
3. An article of manufacture including a yoke having passages therein, a bow having arms in said passages, a key and a plurality of teeth on the arms of the bow for selective engagement with the key.
4. In a brake mechanism for railway cars, the combination of a brake step, a brake chain, a yoke astride the step, a key passing through the yoke and step, a bow connected with the chain and having its legs inserted

in the yoke and engaged at opposite sides 25 with the key.

5. An article of manufacture including a yoke adapted to receive the brake step, a bow having its legs slidably mounted in the yoke and a key passing through the yoke 30 and adjustably securing the legs of the bow to the yoke.

6. An article of manufacture including a yoke adapted to receive a brake step, a bow having its legs slidably mounted in diagonally opposite portions of the yoke, and a key penetrating the yoke and passing between the legs of the bow and effecting a locking engagement with them.

7. In a brake mechanism for railway cars 40 the combination of a brake step, a brake chain, a yoke astride the step, a key securing the yoke to the step, a bow connected with the chain and astride the step and the key, and means for securing the bow to the 45 key.

PERCY B. CAMP.
